UNITED STATES PATENT OFFICE.

JOHN H. KEYS, OF DAYTON, OHIO, ASSIGNOR TO THE DAYTON IRRIGATION COMPANY,
OF DAYTON, OHIO, A CORPORATION OF OHIO.

SPRINKLER.

Application filed August 7, 1922. Serial No. 580,256.

My invention relates to water distribution or irrigation and more particularly to sprinklers of the automatic type.

The invention pertains first, to the automatic actuation of a distributor nozzle through rotary movement by the use of a planetary gear train actuated by a supplemental discharge of water under pressure. This fluid pressure operated rotor which rotates at a comparatively high rate of speed operates through the planetary gear train to rotate the main discharge nozzle at a reduced speed. Second, the invention pertains to a mounting for such automatic sprinkler, whereby the sprinkler is permanently installed in a lawn or other area to be irrigated and is normally concealed in a sunken receiver or container masked by a closure lid carrying a section of turf or sod, which entirely conceals the location of the sprinkler when inoperative. The sprinkler is elevated under fluid pressure carrying upwardly with it the sod carrier or closure, which is returned to the ground level upon retraction of the sprinkler. In the present instance, the sprinkler is actuated by jet arms having a spread much greater than the diameter of the sunken receiver, the jet arms being flexibly connected or jointed for folding into compact relation with the sprinkler upon its retraction into the sunken receiver, and automatically distended upon its elevation to operative position.

The object of the invention is to simplify the structure as well as the means and mode of operation of such automatic sprinklers whereby they will not only be cheapened in construction, but will be more efficient in use, positive in operation, uniform in action, automatic, and unlikely to get out of repair.

A further object of the invention is to provide improved form of automatic driving mechanism whereby the main sprinkler head or distributor nozzle will be slowly rotated under influence of fluid pressure.

A further object of the invention is to provide adjustable jet or propeller arms for such sprinkler heads.

A further object of the invention is to provide an improved mounting for such automatic sprinklers, whereby the sprinkler head may be actuated to and from operative position under fluid pressure control and to provide means for not only concealing the

sprinkler, but for restoring the surface of the lawn, or turf to natural condition upon retraction of the sprinkler head.

A further object of the invention is to provide an improved turf or sod carrier automatically controlled by the fluid pressure for closing the sprinkler receiver or receptacle which will not present obstruction to the passage of a lawn mower, and which when employed on a golf course will permit uninterrupted play across the location of the sprinkler.

With the above primary and other incidental objects in view as will more fully appear in the specification, the invention consists of the features of construction, the parts and combinations thereof, and the mode of operation, or their equivalents as hereinafter described and set forth in the claims.

Referring to the drawings, Fig. 1 is a perspective view of an automatic sprinkler forming the subject matter hereof installed in a lawn, the sprinkler being shown in its elevated or operative position. Fig. 2 is a side elevation of the sprinkler in its retracted position with the receptacle or receiver closed. Fig. 3 is a top plan view of the assembled sprinkler in elevated or operative position. Fig. 4 is an enlarged vertical sectional view illustrating the relation of the operative parts. Fig. 5 is a detail view of the pressure actuated rotor or runner. Figs. 6 and 7 are detail views of modifications of the planetary transmission. Fig. 8 is a detail side elevation of a modification of the rotary sprinkler head. Fig. 9 is a detail sectional view of a modification wherein the annular by-pass is formed in the stem, such being a reversal of the disclosure shown in Fig. 5.

Like parts are indicated by similar characters of reference throughout the several views.

The automatic sprinkler herein shown and described is particularly adapted for installation in gardens, lawns and especially upon golf courses. The sprinkler is designed to be permanently installed and supplied with water under pressure through underground pipes or conduits leading from a suitable source of supply. When inoperative the sprinkler is not only concealed or masked, but the closure for the receiver agrees in appearance exactly with the sur-

rounding surface of the ground and presents no obstruction to a lawn mower and affords an even uniform surface which renders it particularly desirable upon golf courses, and analogous locations.

Referring to the accompanying drawings, wherein is shown the preferred, but obviously not necessarily the only embodiment of the invention, 1 is a sunken receiver or enclosure for the sprinkler head, which enclosure or receiver is embedded in the earth. This receiver 1 is preferably of cylindrical form, the bottom of which is provided with a spud or boss 2 for attachment of a vertical supply pipe 3. This supply pipe communicates with a suitable source of supply of water under pressure. Telescopically engaged in the vertical pipe 3 is a reciprocatory tubular stem 4, having at its lower end an enlarged head 5, which approximately fits the interior of the pipe 3, forming therein a piston head subjected to the pressure of the water. This reciprocatory telescopic stem 4 is provided with a sliding bearing 6 in the bottom of the receptacle or receiver 1. This bearing is preferably though not necessarily a babbitt bearing or of other construction affording a suitable wear resistance but comparatively tight joint. The head 5 of the stem, may if desired, be provided with packing rings or an annular collar of packing material intermediate the periphery of the head and the interior wall of the pipe 3. However, in practice, such construction has not been found necessary under ordinary conditions of use. The distributor head and actuating mechanism therefor, are carried by the reciprocatory stem 4. The distributor comprises a nozzle 7, which may be of any suitable or desired construction, but is preferably similar to the ordinary type of hose nozzle in common use. This nozzle is mounted at an inclination to the vertical upon the upper end of a revoluble trunnion stem 8. This hollow trunnion shaft 8 is revolvably mounted in a bearing head 9, fixedly secured upon the upper end of the reciprocatory shaft 4. In the present instance, the bearing head 9 has been shown counter-bored to form an interior shoulder or thrust bearing 10, which co-acts with a peripheral flange 11, formed integrally at the extremity of the revoluble trunnion stem 8. Anti-friction washers 12 are preferably interposed between the peripheral bearing flange 11 and the shoulder 10. In order to facilitate the assembly of the device and permit the insertion of the enlarged head or flanged extremity 11 of the trunnion 8 through the bearing head 9, the latter is provided with a bushing 13, engaged within the head 9 beyond the peripheral flange 11 of the trunnion, and within which is screw threaded the upper end of the reciprocatory plunger or stem 4. The construction is such that the nozzle 7 carried

upon the revoluble hollow trunnion 8 is vertically movable in unison with the reciprocation of the plunger 4, but is capable of rotation independent thereof within the bearing head 9, fixedly connected to the plunger. 70 In the preferred form of construction shown in detail in Fig. 4, the bearing head 9 carries a spur gear 14 fixedly secured thereto and hence non-rotatable. Secured to the revoluble hollow trunnion 8 is a second spur gear 75 15, concentric with the stationary gear 14 and rotatable in relation therewith. This gear 15 is secured upon the hollow trunnion stem 8 by means of a set screw 16, or by a suitable key or other attachment means. 80 Loosely journaled upon the hollow trunnion 8, above the spur gear 15 for independent rotary movement upon the trunnion, is a runner or rotor. This rotor comprises a sleeve 16, having a running fit upon the 85 trunnion, the base of which is extended in a flanged disc 17 to form an enclosing housing for the gears 14 and 15. This flanged disc or housing 17 is provided with a segmental extension 18 at one side enclosing a gear pinion 19, pivotally mounted upon a suitable stub 20, and intermeshing with both gears 14 and 15. 90

Formed within the interior of the runner or rotor sleeve 16 is an annular groove or internal recess 21, registering with discharge orifices 22 in the tubular trunnion 8. Extending radially from the rotor sleeve 16 are short conduits or tubular arms 23 communicating with the annular groove or recess 21. Pivoted or otherwise flexibly connected with these short tubular arms 23 are jet arms or propeller arms 24. These arms have at their extremity, one or more small perforations or outlet orifices 25 through which are discharged jets of water under pressure, the reaction of which serve to rotate the sleeve 16 and housing 17 about the trunnion 8. The housing disc 17, carries stop fingers 26 which form rests for the jet or propeller arms 24 when extended. These arms 24 also carry stop studs 27 in the present instance, merely a screw, which engage the under sides of the stop fingers 26 to limit the retractive or folding movement of the arms. The gear housing 17 is formed with an enlargement 28 at one side which affords a counter-balance for the pinion 19. The gears 14 and 15 are nearly the same size but vary slightly, one having one or a few more teeth than the other. In practice, sprinkler heads have been constructed, wherein one of these gears contains fifty-nine teeth and the other sixty, while the pinion contains fourteen teeth. In other instances, one of the gears is provided with a hundred and six teeth, while the other gear has one hundred and four teeth. However, the proportions of these gears may be varied according to 125 conditions of use and the desired relative 130

rate of rotation of the main nozzle 7 and runner or rotor 16. As the runner or rotor revolves upon the trunnion 8, under the influence of the reaction of the jets discharged from the arms 24, the pinion 19 will be carried around and around the gear. It will travel around the stationary gear as a rack. Due to the unequal number of teeth in the gears 14 and 15, it will cause a small relative adjustment of these gears in relation with each other. The gears being so nearly the same size and the number of teeth being so slightly different, the single pinion will readily intermesh with both gears. However, if any considerable variation in size of gears is made a correspondingly stepped pinion should be provided. The direction of rotation of the independently revoluble gear 15 and the nozzle 7 is dependent upon whether such gear 15 is larger or smaller than the gear 14. By reversing these gears, that is substituting the larger for the smaller, and vice versa, the direction of rotation of the nozzle may be reversed. The gears, however, are preferably though not necessarily arranged to rotate the nozzle 7 in the same direction as the rotation of the runner or rotor 16 but at a reduced rate of speed. The nozzle may, however, by interchange of the gears as before described, be made to rotate in a direction reverse of the direction of rotation of the rotor 16.

As a modification of the planetary gear transmission, illustrated in Fig. 6, a gear 15' is carried by the runner or rotor 16 and rotates in relation therewith. This gear meshes with a pinion 19' carried upon an arm 29 secured to the revoluble trunnion 8. The gear pinion 19' also meshes with the gear 14. In this arrangement, the gear 15' is the driver, while the pinion is the driven member. In the primary construction shown in Fig. 4 the pinion 19 is the driving member, while the gear 15 is the driven member. The modification shown in Fig. 7 differs from both of these by mounting the gear 19'' upon an arm 30 fixedly secured to the bearing head 9. This pinion 19'' meshes with the driver gear 15' carried by the runner or rotor 16 and also with the driven gear 14' which in this case is mounted upon the trunnion 8. Whichever construction is employed the ultimate result will be substantially the same. Projecting upward from the distributor nozzle 7 is a standard or strut 31, which carries a sod pan or closure lid 32 for the receptacle 1. This pan is of a diameter substantially agreeing with the receptacle 1 and is adapted to fit within the top of the receptacle when the sprinkler head is retracted. The pan or closure 32 is of sufficient depth to carry a piece of sod or turf and ample soil to keep the grass alive. The standard or strut 31 is of such length, that when the sprinkler head

is retracted to the full limit of its downward movement, the closure pan will be drawn within the mouth of the receptacle 1 to afford a uniform surface with the surrounding lawn. The downward movement of the sprinkler head is limited by the engagement of the head 9 or the bushing 13 with the bottom of the receptacle, so that there is little or no strain transmitted to the sod pan 32.

In operation when the water is turned on from a distant control valve, the water pressure within the pipe 3 acting upon the lower end or head of the telescopic plunger 4, will elevate the plunger carrying the sprinkler head and receptacle closure upwardly until the distributor head is above the level of the surrounding lawn surface. In this upward movement the arms 24 fall outwardly by gravity. However, if they do not immediately fall the discharge of water through such arms and the centrifugal tendency of the rotating head will carry the arms to the full limit of their outward movement. The reaction of the discharge jets of water rotates the runner or rotor 16, which acting through the planetary gear transmission serves to rotate the nozzle 7 at a reduced rate of speed. This nozzle 7 may be adjusted to discharge a stream to any desired distance. The intermediate area in close proximity to the location of the sprinkler head will be amply irrigated by the jets discharged from the propeller arms 4. Upon shutting off the water supply at the distant valve, the fluid pressure being relieved, the sprinkler head will descend by gravity. The engagement of the propeller arms 24 with the edge of the receptacle 1 serves to flex these arms upwardly about their pivotal or jointed connection with the head, into a compact form to enter the receptacle 1. At the final limit of its descent, the sprinkler head will draw the closure plan 2 into engagement with the open top of the receptacle.

The closure pan 32 is preferably, though not necessarily provided with a central eye or loop 33, which may be engaged by a suitable hook or other tool to lift the sprinkler head for inspection and repairs without the necessity of turning on the water pressure.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the inven-

tion is not limited to the specific details shown, but that the means and construction herein disclosed comprises the preferred form of several modes of putting the invention into effect and the invention is therefore claimed in any of its forms or modifications within the legitimate and valid scope of the appended claims.

Having thus described my invention, I

10 claim:

1. In an automatic sprinkler, two revoluble sprinkler heads rotating at different rates of speed, a support therefor, and a planetary gear train comprising two gears 15 of different size and a third gear meshing with both the first mentioned gears, the gears of said planetary train being connected one with each sprinkler head and one with the support.
- 20 2. The combination with two relatively revoluble nozzles, and a support therefor, one of said nozzles being operated by fluid pressure, and a planetary gear train for transmitting motion from one nozzle to the other.
- 25 3. A sprinkler including in combination, a tubular stem to which water is supplied under pressure, a slow rotating long range discharge nozzle mounted upon said stem and deriving its water supply therefrom, a high
- 30 speed, short range reaction distributor head also mounted upon said stem and receiving its supply of water therefrom, the long range slow rotating nozzle being adapted to discharge above and beyond the range 35 of water discharged from the high speed short range head, and means for effecting the rotation of the nozzle simultaneously with the rotation of said distributor head.
4. In an automatic sprinkler, a nozzle 40 mounted for pivotal movement, a gear member movable with the nozzle, a support for the nozzle, a stationary gear member carried by the support, the effective magnitude of which is different from that of the nozzle gear, a rotary sprinkler head, and a planetary pinion carried by the sprinkler head and simultaneously intermeshing with the stationary support gear and the movable nozzle gear to transmit pivotal movement
- 45 to the nozzle.
5. In an automatic sprinkler, a revoluble discharge nozzle, a reaction sprinkler head, a support upon which the nozzle and sprinkler head are mounted for rotary movement,
- 55 a gear train including a pair of gear members of like diameters but having different numbers of teeth, one of said gear members being mounted upon the nozzle and the other upon the support, and a planetary gear pinion carried by the reaction sprinkler head and simultaneously meshing with the said nozzle and support gears, and by its travel effecting a differential movement thereof to rotate the nozzle at a reduced
- 60 rate of speed.

6. In an automatic sprinkler, two rotary sprinkler heads, revoluble at different rates of speed, one of the sprinkler heads being fluid pressure actuated, said sprinkler heads being concentrically mounted, a pair of 70 gears of different magnitude also mounted concentrically with said sprinkler head and a gear pinion common to both gears, one of said gears being operatively connected with one of the sprinkler heads, one of the 75 gears being held stationary, and the other gear being carried by the other sprinkler head, whereby motion is transmitted from one sprinkler head to the other.

7. In an automatic sprinkler, a pivoted 80 nozzle, a support therefor, a fluid pressure actuated sprinkler head mounted concentrically with the pivotal connection of the nozzle, and a planetary gear train for transmitting motion at reduced speed from the 85 sprinkler head to the nozzle.

8. In an automatic disappearing sprinkler, a vertically movable nozzle, fluid pressure controlled means for raising and lowering the nozzle, a sunken chamber into which 90 the nozzle is lowered, and a sod carrier movable up and down with the nozzle and forming a closure for the nozzle receiving chamber.

9. In a disappearing sprinkler, the combination with a sunken receptacle to receive a sprinkler head and a sprinkler head movable into and out of the sunken receptacle, of a pan like closure for said receptacle to contain a section of turf and means by 100 which the pan is automatically moved into and out of closing position in accordance with the movement of the sprinkler head into and out of the receptacle.

10. In a disappearing sprinkler, the combination with a sunken receptacle to receive a sprinkler head movable into and out of the receptacle, of a sod pan forming a closure for the receptacle, and adapted to contain a section of turf and means for automatically moving the sod pan and its contents into and out of closing position, in relation with the receptacle, in unison with the movement of the sprinkler head.

11. In a construction of the character described, the combination with a sunken receptacle to receive a sprinkler head, of a sod carrier forming a closure for the receptacle, and means controlled by the operation of the sprinkler head for moving the 115 sod carrier into and out of closing relation with the receptacle.

12. In a construction of the character described, the combination with a sunken receptacle to receive a sprinkler head, of a 120 sod carrier forming a closure for the receptacle, and carried by the sprinkler head.

13. In a disappearing sprinkler, two relatively rotatable distributors revoluble in unison at different rates of speed, one of said 130

distributors having substantially radially disposed jet arms foldable to and from positions substantially parallel with the axis of rotation, means for raising and lowering the distributor heads and means for extending and retracting the jet arms in unison with the vertical movement of the distributor heads.

14. In a disappearing sprinkler, two sprinkler heads relatively rotatable in relation with each other including a plurality of radially adjustable jet arms, a sunken receptacle into which the sprinkler heads are retractable, means for raising and lowering the sprinkler heads out of and into the sunken receptacle, said radially adjustable arms being retracted when said heads are within the receptacle.

15. A sprayer comprising in combination, a vertical tubular support having means for connection with a water supply, a reaction sprinkler head rotatably mounted on said support and deriving its water supply therefrom, a nozzle rotatably mounted on said support and communicating therewith and disposed at a higher elevation than said head, and means for positively rotating the nozzle at a reduced speed from the reaction sprinkler head.

16. A sprayer comprising in combination, a vertical tubular support having means for connection with a water supply, a reaction sprinkler head rotatably mounted on said support and deriving its water supply therefrom, a nozzle rotatably mounted on said support and communicating therewith and disposed at a higher elevation than said head, and means for positively rotating the nozzle at a reduced speed from the reaction sprinkler head, said rotating means

comprising a reduction gear train between said reaction sprinkler head and said nozzle.

17. A sprinkler comprising in combination, a central tubular stem rotatably mounted to turn on a vertical axis, a nozzle secured to the upper end of the stem, a reaction sprinkler head rotatably mounted on the tubular stem and deriving its water supply therefrom, and means for positively driving the central tubular stem at a reduced speed from the reaction sprinkler head.

18. A sprinkler, comprising the combination with a hollow head to which a water supply under pressure is delivered, a central tubular stem rotatably mounted in the head to project from its upper end and retained against endwise movement therein, said stem having a nozzle secured to its upper end to angularly project therefrom, a reaction sprinkler head rotatably mounted on the central stem and deriving its water supply therefrom, and means for positively rotating the central stem from the reaction sprinkler head.

19. A sprinkler, comprising the combination with a hollow head to which a water supply under pressure is delivered, a central tubular stem rotatably mounted in the head to project from its upper end and retained against endwise movement therein, said stem having a nozzle secured to its upper end to angularly project therefrom, a reaction sprinkler head rotatably mounted on the central stem and deriving its water supply therefrom, and means for mechanically connecting the reaction sprinkler head to the central tubular stem to rotate it.

In testimony whereof, I have hereunto set my hand this 1st day of August A. D. 1922.

JOHN H. KEYS.
